UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,471, dated December 11, 1883.

Application filed July 23, 1883. Term of patent 3½ years.

To all whom it may concern:

Be it known that I, WINTHROP L. JACOBS, of East Orange, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

15 The ground consists of scattered circular

and right-lined figures with smaller intervening leaf-like forms on short inconspicuous stems. On this ground, at regular intervals, are placed various large and small figures of various radial and circular shapes. They are 20 shown in the photograph as without stem-connections, although this is not essential to the design.

I claim--

The design for a carpet, substantially as 25 shown and described.

WINTHROP L. JACOBS.
